CLAIM

The ornamental design for a frame section, as shown and described.

DESCRIPTION

FIG. 1 is a perspective view of a frame section showing my new design.

FIG. 2 is a right side elevational view thereof, with the left side elevational view being a mirror image thereof.

FIG. 3 is a top plan view thereof.

FIG. 4 is a front elevational view thereof.

FIG. 5 is a bottom plan view thereof.

FIG. 6 is a rear elevational view thereof; and,

FIG. 7 is a perspective view of the frame section of FIG. 1 shown in an environment of use with a display unit.

The appearance of any portion of the frame section between the symbolic break lines forms no part of the claimed design. Broken lines in FIG. 7 depict environmental subject matter and form no part of the claimed design.
